UNITED STATES PATENT OFFICE

ERIC C. HUGHES, OF WEST SACRAMENTO, CALIFORNIA, ASSIGNOR TO THE POPSICLE CORPORATION OF THE UNITED STATES, OF NEW YORK, N. Y., A CORPORATION OF DELAWARE

CONTAINER FOR FROZEN FRUIT JUICE, SHERBETS, ICE CREAM, AND THE LIKE

Application filed June 10, 1931. Serial No. 543,457.

This invention relates to certain new and useful improvements in container for frozen fruit juices, sherbets, ice cream and the like.

The primary object of the invention is to provide a container for frozen fruit juice, sherbets, ice cream and like comestibles wherein the container is struck from a single blank of sheet material to be folded into box or container formation and embodying means to effect discharge or removal of the frozen material from the container.

A further object of the invention is to provide a container of the foregoing character wherein the bottom wall construction thereof includes a section extending from one end wall of the container with the outer section of the bottom wall construction designed to permit upward movement of the upper section of the bottom wall for partially or entirely removing the frozen contents from the container.

With the above and other objects in view that will become apparent as the nature of the invention is better understood, the same consists in the novel form, combination and arrangement of parts hereinafter more fully described, shown in the accompanying drawings and claimed.

In the drawings:—

30 Figure 1 is a perspective view of a container constructed in accordance with the present invention, showing the upward arched side walls of the container;

35 Figure 2 is a vertical longitudinal sectional view taken on line 2—2 of Figure 1, showing the overlapping flap sections carried by the end walls of the container;

40 Figure 3 is a vertical cross-sectional view taken on line 3—3 of Figure 1;

45 Figure 4 is a vertical longitudinal sectional view, similar to Figure 2, showing the upper section of the bottom wall construction partly elevated by a cut out tab in the lower section of the bottom wall;

Figure 5 is a bottom plan view of the container showing the stuck out tab; and

Figure 6 is a developed plan view of the blank from which the container is formed.

Referring more in detail to the accompanying drawings and more particularly to Figure 6, there is illustrated a blank of sheet material of any preferred character from which the container is formed including all wall structures and creased or weakened on certain lines to permit folding of the blank into container formation, the reference numeral 10 designating a central rectangular portion constituting the bottom of the container and at each side of which extends a side wall 11 foldable upon the lines 12, the outer edges of the side walls 11 being upwardly arched as at 13. Each side wall 11 carries an end extension flap 14 that is foldable upon the line 15, the inner edges of the flap 14 terminating in line with the fold line 12 while the outer edges of said flaps terminate at the arched edges 13 of the side walls 11.

An end wall construction is carried by each end of the bottom section 10 and includes a section 16 foldable upon the line 17 and a second section 18 foldable upon the line 19. One end wall section 18 carries a flap section 20 which occupies a position above the bottom section 10 when the blank is folded to extend partly across the bottom section 10 while the other end wall section 18 carries a relatively long bottom flap section 21 that when the blank is folded occupies a position co-extensive with the bottom section 10. Both sections 20 and 21 being foldable upon the lines 22. The bottom wall section 10 carries a centrally located tab 23 cut from the bottom upon the lines 24 and bendable upon the weakened line 25.

In folding the blank shown in Figures 6 into box, carton or container formation, the side walls 11 are first folded upon the lines 12 and the tabs 14 upon opposite ends of the

side walls 11 are folded upon the lines 15, the opposed edges of the tabs 14 substantially contacting. The end wall sections 16 are then folded upon the lines 17 into engagement with the tabs 14 and the sections 18 are then folded upon the lines 19 for engagement with the inner sides of the tabs 14, the end section 20 being foldable upon the line 22 to overlie the bottom wall section 10. The longer flap section 21 is folded upon the line 22 to overlie the section 20 and bottom wall section 10. The blank is folded into container formation as illustrated in Figures 1 to 5. The end walls are of reinforced character as will be understood from an inspection of Figures 2 and 4, each end wall comprising double plies of material while the side walls 11 are retained in locked position by the tabs 14 carried thereby extending between the sections 16 and 18 of the end walls. When it is desired to remove the frozen commodity from the container, pressure is exerted against the tab 23 to effect upward movement of the relatively short and long flap sections 20 and 21 overlying the bottom wall section 10 as illustrated in Figure 4 and the frozen commodity can be completely removed from the container if desired.

While there is herein shown and described the preferred embodiment of the present invention, it is nevertheless to be understood that minor changes may be made therein without departing from the spirit and scope of the invention as claimed.

25 I claim:—

1. In a container of the character described, a receptacle having side, end and bottom walls, the bottom wall including a main bottom section and an overlying bottom section 40 extending from one end wall and a hinged tab in the main bottom section permitting upward projection of the overlying bottom section for ejection of the contents of the receptacle.
- 45 2. In a container of the character described, a receptacle having side, end and bottom walls, the bottom wall including a main bottom section and an overlying bottom section extending from one end wall, a hinged tab 50 in the main bottom section permitting upward projection of the overlying bottom section for ejection of the contents of the receptacle, and the overlying bottom section completely covering the main bottom section.
- 55 3. In a container of the character described, a receptacle having side, end and bottom walls, the bottom wall including a main bottom section and an overlying bottom section 60 extending from one end wall, a hinged tab in the main bottom section permitting upward projection of the overlying bottom section for ejection of the contents of the receptacle, and a relatively shorter overlying bottom section carried by the other end wall and underlying 65 the first named overlying bottom section.

4. In a container of the character described, a receptacle having side, end and bottom walls, the bottom wall including a main bottom section and an overlying bottom section 70 extending from one end wall, a hinged tab in the main bottom section permitting upward projection of the overlying bottom section for ejection of the contents of the receptacles, the overlying bottom section completely covering the main bottom section, and a relatively shorter overlying bottom section carried by the other end wall and underlying the first named overlying bottom section.

5. In a container of the character described, a receptacle having side, end and bottom 80 walls, the bottom wall including a main bottom section and an overlying bottom section extending from one end wall and a hinged tab in the main bottom section permitting upward projection of the overlying bottom section for ejection of the contents of the receptacle, the end walls comprising foldable sections carried by the main bottom section with the foldable sections arranged in parallelism and end tabs on the side walls disposed between the parallel sections of the end walls.

6. In a container of the character described, a receptacle having side, end and bottom walls, the bottom wall including a main bottom section and an overlying bottom section 95 extending from one end wall, a hinged tab in the main bottom section permitting upward projection of the overlying bottom section for ejection of the contents of the receptacle, the overlying bottom section completely covering the main bottom section, the end walls comprising foldable sections carried by the main bottom section with the foldable sections arranged in parallelism and end tabs on the side walls disposed between the parallel sections of the end walls.

7. In a container of the character described, a receptacle having side, end and bottom walls, the bottom wall including a main bottom section and an overlying bottom section 115 extending from one end wall, a hinged tab in the main bottom section permitting upward projection of the overlying bottom section for ejection of the contents of the receptacle, a relatively shorter overlying bottom section carried by the other end wall and underlying the first named overlying bottom section, the end walls comprising foldable sections carried by the main bottom section 120 with the foldable sections arranged in parallelism and end tabs on the side walls disposed between the parallel sections of the end walls.

8. In a container of the character described, a receptacle having side, end and bottom 125 walls, the bottom wall including a main bottom section and an overlying bottom section extending from one end wall, a hinged tab in the main bottom section permitting upward projection of the overlying bottom section 130

for ejection of the contents of the receptacles,
the overlying bottom section completely cov-
ering the main bottom section, a relatively
shorter overlying bottom section carried by
5 the other end wall and underlying the first
named overlying bottom section, the end walls
comprising foldable sections carried by the
main bottom section with the foldable sec-
tions arranged in parallelism and end tabs on
10 the side walls disposed between the parallel
sections of the end walls.

In testimony whereof I affix my signature.
ERIC C. HUGHES.
